(57) **CLAIM**

The ornamental design for a laboratory instrument, as shown and described.

DESCRIPTION

FIG. 1 is a left-front perspective view of a laboratory instrument;

FIG. 2 is a front view of the laboratory instrument of FIG. 1;

FIG. 3 is a rear view of the laboratory instrument of FIG. 1; FIG. 4 is a left-side view of the laboratory instrument of FIG. 1;

FIG. 5 is a right-side view of the laboratory instrument of FIG. 1;

FIG. 6 is a top view of the laboratory instrument of FIG. 1; FIG. 7 is a bottom view of the laboratory instrument of FIG. 1;

FIG. 8 is a right-rear perspective view of the laboratory instrument of FIG. 1;

FIG. 9 is a left-front perspective view of the laboratory instrument of FIG. 1 with a filter rack open;

FIG. 10 is a left-front perspective view of the laboratory instrument of FIG. 1 with a front flap open;

FIG. 11 is a left-front perspective view of the laboratory instrument of FIG. 1 with a slide drawer open; and,

FIG. 12 is a left-front perspective view of the laboratory instrument of FIG. 1 with a drawer open.

The broken lines in the figures represent portions of the laboratory instrument that form no part of the claimed design.

1 Claim, 12 Drawing Sheets
